UNITED STATES PATENT OFFICE.

CHARLES HENRY STAVE, OF THORNTON, ILLINOIS.

PEBBLE OR BALL MILL.

1,283,589.

Specification of Letters Patent.

Patented Nov. 5, 1918.

Application filed March 4, 1918. Serial No. 220,209.

To all whom it may concern:

Be it known that I, CHARLES H. STAVE, a citizen of the United States, and a resident of Thornton, in the county of Cook and

5 State of Illinois, have invented a new and Improved Pebble or Ball Mill, of which the following is a description.

My invention relates to a grinding or reducing mill adapted to receive balls or pebbles and mounted to be turned, whereby the material is reduced by the action of the balls or pebbles with the turning of the mill.

10 The invention more particularly relates to a mill designed to reduce chemicals or other materials to fine powder.

15 The prime object of the invention is to provide a pebble or ball mill in which the drum or cylinder will be disposed with its axis transecting the axis about which the mill turns whereby to effect increased reducing action by a more frequent and more thorough tumbling of the reducing elements and the material.

20 Reference is to be had to the accompanying drawings, it being understood that the drawings are merely illustrative of one example of the invention.

25 Figure 1 is a side elevation of a mill embodying my invention;

30 Fig. 2 is a plan view thereof;

Fig. 3 is a longitudinal vertical section thereof as indicated by the line 3—3, Fig. 2.

In the illustrated example a suitable base 10 is provided having standards 11 provided at the top with bearings 12 on which the trunnions 13 of the mill turn, one of the trunnions having a suitable handle 14 or other means whereby the mill may be turned.

35 The trunnions are on a frame or holder 40 designated generally by the numeral 15. The drum or cylinder 16 in my improved mill is carried by frame or holder 15, to the ends 15^a of which the trunnions are secured. The holder is equipped with means to clamp

45 the drum 16 in position with its axis transecting the axis of rotation of the holder. In the illustrated example the holder frame 15 is open at the center to receive the cylinder or drum and is provided with clamp means

50 in the form of a frame 17 which is also open at the center for the accommodation of the cylinder. The frame 17 is secured to the frame 15 by any suitable means, here shown as bolts 18, having wing nuts 19, the bolts 55 extending from the frame 15 through slots 20 in said frame 17. At each end of the

holder and at opposite sides thereof, means is provided on the holder frame proper and its clamp frame 17 to engage and retain the cylinder at its ends. In the illustrated form 60 a seat 21 extends from the holder 15 at one side thereof, oblique to the general plane of said holder and has an annular flange 21^a in a position to overlap the drum or cylinder and at the opposite end of the holder 15 65 and at the same side as the seat 21 is a concave seat 22 on which the opposite end of the cylinder rests at a side of the cylinder. Similarly, there is provided on the clamp frame 17 an oblique seat 23 having a flange 70 23^a and at the opposite end of said frame 17 there is a concave seat 24, said parts 23, 23^a, 24 corresponding with the parts 21, 21^a and 22. The loosening of the nuts 19 permits the removal of the clamp frame 17 and 75 with it the seats 23, 24, thereby permitting the ready placing or removal of the cylinder when desired. The cylinder is provided with a removable head 25 which is held in position by any suitable means as by a bayonet lock, there being indicated pins 26 on the cylinder and bayonet slots 27 in the head 25. Thus, the removal of the clamp frame 17 readily permits of the removal of the head 25 for charging or emptying the cylinder. 80

It will be seen that with the described construction in the turning of the cylinder about the axis of the holder 15, the material to be reduced and the reducing balls or pebbles 90 will alternately shift from one end of the cylinder toward the other, thereby producing a more effective interchange of the contents of the mill and a more effective grinding impact of the grinding elements. 95

I would state in conclusion that while the illustrated example constitutes a practical embodiment of my invention, I do not limit myself strictly to the mechanical details herein illustrated, since manifestly the same 100 can be considerably varied without departure from the spirit of the invention as defined in the appended claims.

Having thus described my invention, I claim as new, and desire to secure by Letters 105 Patent:

1. A ball or pebble mill including a support, a holder revolvably mounted in said support, a cylinder disposed in said holder in position at an angle thereto and crossing 110 the axis of revolution of the holder, a clamp on the holder at one side, said holder at one

side thereof having seats for said cylinder at opposite ends of the holder, and the said clamp having corresponding seats thereon at its opposite ends.

- 5 2. A ball or pebble mill including a revolute holder, a cylinder in the holder disposed oblique to the axis of revolution of the holder, a seat extending from the holder at one side adjacent to an end of the holder
10 and oblique to the axis of revolution of the holder adapted to engage the cylinder at one end, a similar concave seat on the holder at

the opposite end from the first seat, and at the same side of the holder as said seat, a clamp on the holder at the opposite side 15 from the seats thereof, a seat on said clamp and approximately parallel with the first mentioned seat or holder and at the opposite end of the cylinder, a concave seat on the clamp at the same side as the first seat but 20 at the opposite end of the clamp, and means to detachably secure said clamp in position.

CHARLES HENRY STAVE.
